UNITED STATES PATENT OFFICE.

THEODORE W. WASHBURN, OF BALDWINSVILLE, MASSACHUSETTS,
ASSIGNOR TO GILMAN WAITE, OF SAME PLACE.

LOCKING DEVICE FOR ADJUSTABLE CHAIRS, &c.

SPECIFICATION forming part of Letters Patent No. 595,840, dated December 21, 1897.

Application filed November 30, 1896. Serial No. 613,892. (No model.)

To all whom it may concern:

Be it known that I, THEODORE W. WASHBURN, of Baldwinsville, in the county of Worcester and State of Massachusetts, have 5 invented a new and useful Locking Device for Adjustable Chairs, Tables, and the Like, of which the following is a specification, reference being had to the accompanying drawings, in which—

10 Figure 1 is a perspective view of an adjustable chair to which my locking device is applied. Fig. 2 is a detail elevation, and Fig. 3 is a detail elevation of the connection between legs B and the chair-seat legs. Figs. 4, 5, 15 and 6 show two castings which form the locking device detached from the chair.

Chairs and tables and the like which are adjustable in height and which consist, essentially, of two pairs of legs pivoted together at 20 or near a point midway of their length and supporting by means of pivots and links upon their upper ends a chair-seat or table-top and having means for controlling the position of the legs with relation to one another are well 25 known.

My invention relates to chair-irons for folding chairs; and it consists, mainly, in a base-plate carrying a hub and a segment, all integral, the segment being notched to receive a 30 pawl, in combination with a second base-plate with two projections integral with the base-plate, one to coöperate with the hub and the other to sustain the pawl, the two irons being connected by the pivot-bolt and the base-plate 35 of one being connected with one leg, while the base-plate of the other is connected with the other leg, so that the legs are connected together when the hub and one of the projections are connected by the pivot-bolt, and 40 the legs can be held at various angles by causing the pawl to engage the different notches in the segment.

In the drawings the base-plate of the segment G and hub g is secured to leg E, and 45 the base-plate with the two projections B' and b is secured to leg B, and these two castings

G g and B' b are connected by the pivot-bolt, and the pawl H then engages one of the notches in segment G. The pawl H is pulled in one direction by the spring h' and in the 50 other direction by the rod and handle H².

The novelty of my contrivance resides in making the segment and hub integral with the base-plate and the projection B' and the pawl-carrying projection b integral with a 55 second base-plate and combining them by means of the pivot-pin and the pawl. This connection makes the most strong and durable connection for such a chair yet produced. The base-plate of part g also gives additional 60 strength to the pivot-point, and the strain is distributed by the connections over a considerable length of the legs B and E.

I have shown my invention as applied to a well-known form of adjustable chair, in which 65 the chair-seat, having the usual short legs, is marked A, and the front legs, which are also rockers, are marked B. The rear legs of the chair-seat A are connected to legs B by the irons B'' and a, and the front legs of chair-seat A are connected to legs E by links F, 70 all as will be well understood without further description.

My mechanism for connecting the crossed legs B and E is especially desirable in that 75 class of chairs in which the legs B form rockers when in one position, for the reason that the projections B' hold legs E above legs B when the chair is used as a rocking-chair.

What I claim as my invention is—

80 The improved connecting mechanism for the crossed legs B and E, comprising a base-plate carrying notched segment G and hub g, secured to leg E; a base-plate carrying projections B' and b secured to leg B; pawl H pinned to projection b; and a pivot-pin connecting hub g and projection B', combined substantially as described.

THEODORE W. WASHBURN.
